UNITED STATES PATENT OFFICE.

JAY A. LIVESAY, OF SAN DIEGO, CALIFORNIA.

CLOTHES-CLEANING BRUSH.

Application filed September 5, 1923. Serial No. 660,992.

My invention relates to clothes cleaning brushes, particularly to a brush which supplies a cleaning liquid to the bristles coming in contact with and adapted to clean clothes, and the objects of my invention are: First, to provide a brush of this class which has a cleaning liquid supply tank in connection therewith; second, to provide a brush of this class in which a liquid supply tank serves 10 also as a handle for the brush; third, to provide a novelly constructed, easily operated and readily accessible valve for discharging the cleaning liquid from the tank to the bristles; fourth, to provide novel 15 means for distributing the cleaning liquid to the different bristles; fifth, to provide a means in connection with a brush of this class whereby the cleaning liquid will flow to and through the bristles in small, limited 20 quantities; sixth, to provide as a whole a novelly constructed brush of this class, and seventh, to provide a clothes cleaning brush of this class which is very simple and economical of construction, durable, efficient, 25 and which will not readily deteriorate or get out of order.

With these and other objects in view, as will appear hereinafter, my invention consists of certain novel features of construction, 30 combination and arrangement of parts and portions as will be hereinafter described in detail and particularly set forth in the appended claim, reference being had to the accompanying drawings and to the characters of reference thereon, which form a part 35 of this application, in which:

Figure 1 is a side elevational view of my clothes cleaning brush; Fig. 2 is a longitudinal, sectional, elevational view thereof, taken through 2—2 of Fig. 3; Fig. 3 is a transverse, sectional, elevational view thereof, taken through 3—3 of Fig. 2, and Fig. 4 is a fragmentary, plan view of my brush.

Like characters of reference refer to similar parts and portions throughout the several views of the drawings.

The bristle supporting member 1, bristles 2, tank members 3 and 4, screws 5, cap receiving member 6, cap 7, resilient member 8, 50 valve leather support 9, valve leather 10, valve knob 11, and the plastic material 12, constitute the principal parts and portions of my clothes cleaning brush structure.

The bristles 2 of my brush are supported 55 by and in the bristle supporting member 1, preferably of wood or any other suitable

material, and extend downwardly therefrom, the outer row of bristles being preferably directed outwardly at a slight angle. The bristle supporting member 1 is provided with a plurality of reduced holes 1^a, extending from the inner side thereof to the inner ends of the bristles 2, through which the cleaning liquid flows to the ends and thence through the bristles to the outer ends thereof. The cleaning liquid supply tank consists of a tank member 3 having a bottom 4 secured thereto in any convenient manner, which bottom member separates the contents of the tank from the space between the bottom and the bristle supporting member 1. The tank, being provided with a continuous, downwardly extending flange, is secured to the outer edge of the bristle supporting member 1 by means of the screws 5 extending through the flange of said tank. At the upper portion of the tank member 1 and near one end thereof is provided a cap receiving member 6 for filling the tank with the cleaning liquid, a cap 7 being adapted to be secured in the member 6. The side walls of the tank member 3 are preferably made receding inwardly towards their upper portions, the long side walls thereof being provided with elongated, inwardly extending, curved recesses 3^a into which the fingers of the user of the brush are adapted to extend for securely gripping the same. Near one end of the bottom member 4 is provided an opening 4^a for discharging the cleaning liquid from the same to the bristles. I have provided a resilient valve member 8, preferably curved, positioned in the space between the bottom of the same and the top of the bristle supporting member 1 and extending transversely therethrough. The one end of said member 8 is bent downwardly and secured between the bristle supporting member 1 and the downwardly extending flange of the tank member 3 by means of a screw 5 extending through and into said members. The other end of said member 8 extends through the tank members 3 and 4, as shown best in Fig. 3 of the drawings, and is provided at its outwardly extending end with a knob 11 for operating the valve. Intermediate the ends of the resilient valve member 8, in line with the opening 4^a in the tank member 4, is the valve leather supporting member 9, preferably a conventional split rivet extending through and secured to the

member 8, preferably by spreading the split end of said rivet, as shown in the drawings. Intermediate the tank member 4 and the member 9, and supported by the head of said rivet, is a valve leather 10, which is positioned against the member 4 over the opening thereof by means of the inherent spring of the member 8.

It will be noted that when exerting a force 10 on the knob 11, the resilient valve member 8 being slightly curved when the valve is closed, will be distorted to a greater extent, as shown by dotted lines in Fig. 3 of the drawings, and open the valve, permitting the 15 cleaning liquid from the tank to flow onto the bristle supporting member 1, distributing the liquid thereon.

There is preferably provided plastic material 12 between the downwardly extending 20 flange of the tank member 3 and the outer edges of the bristle supporting member 1 to rigidly support the member 1 therein and also to prevent unnecessary loss of the cleaning fluid.

It is obvious from this construction as illustrated in the drawings and described in the foregoing specification that there is provided a brush structure as aimed at and set forth in the objects of the invention, and 30 though I have shown and described a partic-

ular construction, combination and arrangement of parts and portions, I do not wish to be limited to this particular construction, combination and arrangement, but desire to include in the scope of my invention the construction, combination and arrangement substantially as set forth in the appended claim. 35

Having thus described my invention, what I claim as new and desire to secure by Letters Patent, is:

In a brush of the class described, a bristle supporting member, a tank positioned on one side of said bristle supporting member and secured thereto, and a valve positioned in the 45 passage between said tank and said bristle supporting member, said valve including a resilient bowed member secured at one end to said tank with its free end extending to the exterior of said tank for manipulating the 50 valve, and a valve member positioned intermediate the ends of said resilient member and adapted to be positioned over an opening in said tank by means of the inherent spring of the resilient member. 55

In testimony whereof, I have hereunto set my hand at San Diego, California, this 30th day of August, 1923.

JAY A. LIVESAY.
